UNITED STATES PATENT OFFICE.

WALTER L. MITCHELL, OF PICAYUNE, MISSISSIPPI.

RAIL-TIE.

1,242,836.

Specification of Letters Patent.

Patented Oct. 9, 1917.

Application filed June 20, 1916. Serial No. 104,737.

To all whom it may concern:

Be it known that I, WALTER L. MITCHELL, a citizen of the United States, residing at Picayune, in the county of Pearl River and 5 State of Mississippi, have invented certain new and useful Improvements in Rail-Ties, of which the following is a specification.

This invention relates to rail ties, and more particularly to an improved rail fastening structure.

The primary object of the invention is to provide a rail fastening wherein the driving spike and other similar fastening devices will be eliminated and to substitute 15 therefore, a rail clamping structure which is so applied as to require the least possible number of connecting bolts.

The invention also contemplates the provision of means, whereby the rail clamping structure will be securely held against further movement when once applied, the said 20 means being in form of a locking bolt so constructed as to prevent its accidental removal.

Another important characteristic of the invention, resides in the novel manner in which the rail clamps are received by the tie, the same being so positioned as to prevent lateral movement thereof, further, to 25 afford an effective bracing means.

The invention also aims to provide a tie of the character described, which is extremely simple in construction, thus reducing the cost of manufacture to a minimum 35 and one which will be strong and durable in use and, finally, highly efficient for the purpose for which it is designed.

All of the foregoing, together with additional advantageous details and arrangements of parts of the preferred embodiment of my invention will be clear from the specific description hereinafter contained, when read in connection with the accompanying drawings forming part thereof, wherein 45 said embodiment of the invention is illustrated for the purpose of facilitating a full understanding of the present improvements.

In the drawings:—

Figure 1 is a perspective view with the 50 various parts of the construction assembled;

Fig. 2 is a perspective with the rail clamps removed;

Fig. 3 is a longitudinal section of the device;

55 Fig. 4 is a detail plan view partly in section showing the locking bolt as first applied;

Fig. 5 is a similar view showing the locking bolt in position; and

Fig. 6 is a detail in perspective view of the locking bolt.

60

Referring now more particularly to the drawings, wherein like reference characters designate like or corresponding parts throughout the several views thereof, the invention may be said to comprise a base 65 portion 1, having arranged thereupon, preferably centrally thereof, a plurality of inclined upstanding flanges 2, 3, and 4 respectively. The central or middle inclined flange 3 has formed adjacent its 70 enlarged extremity, a rail receiving and supporting chair 5, which chair is provided with a rail supporting portion as at 6, the same being of a length to conform to the width of the base portion 1, while 75 its under face is tapered as at 7 and merges with said base portion 1 as at 8, thus, allowing the same to be rigidly supported. The rail supporting portion 6, has arranged adjacent its outer extremity, an offset laterally 80 extending extension 9, and has arranged therein, intermediate its ends, a recessed seat 10. The rail chair 5 is provided with the usual rail engaging and supporting flange 11, which flange braces the base portion of 85 the rail and is of such size as to serve as means whereby the web of the rail may be also braced, at a point, adjacent its base portion. The middle tapered or inclined flange has arranged thereupon, intermediate 90 its ends, an enlargement 12, which enlargement is so constructed as to afford substantially beveled or inclined bearing shoulders 13, the purpose of which shall be hereinafter more fully described, while, ar- 95 ranged in close proximity to said enlargement is an L-shaped slot 14. Positioned adjacent the smaller extremity of flange 3, is a second rail receiving and supporting chair 15, which chair is constructed in exact ac- 100 cordance with the chair 5, the rear end thereof being supported by the flange 4. It may be stated that the offset portion 9 of the rail receiving and supporting chair 5 is, in turn, engaged and supported or braced 105 by the inclined flange 2, which flange has arranged, adjacent its outer extremities, a second L-shaped slot 16. In order that the hereinbefore described flanges may be so provided as to afford the greatest possible 110 strength, I preferably construct the same with tapered sides 17 and 18, shown to ad-

100

105

110

vantage in Fig. 2 of the drawings, while, in an effort to reduce cost of construction, and, further to lighten the same, I extend longitudinally of the upstanding flanges, 5 an opening or bore as at 19.

Referring now to the rail clamping construction, the clamping member 20, comprising a substantially inverted U-shaped housing having laterally extended flanges 21 and 10 having arranged upon one of its extremities, a rail receiving and supporting chair 22, so constructed as to be similar to the chair 15, the same being provided with a supporting portion 23, which portion is received 15 upon the offset portion 9 and abuts the shoulder formed by the offset connection of the portion 9 with the rail supporting portion 6. A notched or recessed seat, similar to the recessed portion 10, is arranged 20 upon the outer or free extremity of the rail supporting portion 23, so positioned intermediate the ends thereof as to readily align with the recessed portion 10. An inclined supporting leg 24 is formed upon 25 the chair 22 and engages with the laterally extended flanges 21, thus serving as a secondary bracing and supporting means. It is to be also noted, that the sides of the clamping member 20 are flared outwardly, 30 this being due to the tapered construction of the walls, which serve to reinforce the same. The outer extremity of the clamping member 20 is beveled as at 25 and when applied to the flange, the said beveled portion 35 engages with the inclined shoulders 18 afforded by the enlargement 12, consequently forcing the rail chair 22 inwardly, into engagement with the rail supporting portion 6 of the chair 15. Suitable aligned openings 40 are arranged adjacent the beveled portion 25 of the clamping member 20 and, are so positioned as to, when applied over the flange 3, align with the L-shaped slot 14. The locking bolt, designated in its entirety, 45 as at 26 is adapted to be passed through the aligned openings and the L-shaped slot 14, thus, securing the same in the flange 3. Attention is directed to the fact, that the said aligned openings in the clamping member 20 are oppositely disposed, that is to 50 say, one of the openings is substantially rectangular in shape while the remaining opening is rectangular in shape, but is so disposed as to have the longer sides thereof, 55 horizontally disposed. The locking bolt includes a head portion 27 and a threaded shank 28, the said shank having arranged thereupon, adjacent the head 27, a horizontally disposed key portion 29 and a key 60 portion 30, the latter of which is spaced from the former and has its longitudinal axis at right angles to that of the portion 29. When inserting a key in the aforesaid openings, the portion 30 is turned so as to be admitted 65 by the horizontal opening in the

clamping member 20 and is then forced forwardly, until the said portion 30 engages with the opposite side of the clamping member 20, whereupon, the locking member is turned, allowing key 30 to be received by the vertically arranged portion of the L-shaped slot 14. When in this position, the key can be again forced forwardly, the portion 30 engaging the vertically disposed opening in the clamp 20, while the portion 29 engages with the horizontal opening as arranged in the clamping member 20. A locking nut 31 is then turned into engagement with the threaded shank 28, securely holding the bolt in position. A second clamping member 32 is receivable upon the flange 2, this clamping member being constructed in accordance with the clamping member 20, which is constructed so that the U-shaped housing portion thereof is of less length than that portion as arranged upon the clamping member 20. Therefore, it is thought that the description of the clamping member 20 will permit a full understanding of this particular construction. 90

To provide for means, whereby longitudinal movement of the rails 33 may be prevented, I form upon the lower face of the base portion, a depending lug 34, this lug, being received in the seat afforded by the notched or recessed portion 10. 95

While I have herein disclosed the specific embodiment of the invention, it will be apparent to persons skilled in the art, that the invention is capable of embodiment in other forms and devices differing in detail and arrangement from that shown, as may be in keeping with the hereto appended claims. 100

Having thus described the invention, what I claim is: —

1. A rail tie, comprising a base portion, a plurality of vertically disposed inclined flanges arranged upon said base portion, rail receiving and supporting chairs positioned adjacent said flanges, rail clamping members receivable by certain of said flanges and engageable with their respective rails, and means for securing said clamping members to said flanges. 115

2. A rail tie, comprising a base portion, a plurality of vertically disposed inclined flanges arranged upon said base portion, rail receiving and supporting chairs positioned adjacent said flanges, rail clamping members receivable by certain of said flanges and engageable with their respective rails, means for securing said clamping members to said flanges, and means engageable with the rail receiving and supporting chairs for preventing longitudinal movement of the rails. 120

3. A rail tie, comprising a base portion, a plurality of vertically disposed inclined flanges arranged upon said base portion, rail 125

receiving and supporting chairs positioned adjacent said flanges, rail clamping members receivable by certain of said flanges having complementary rail receiving and supporting 5 chairs formed upon their outer ends and engageable with the rails, and means for securing said clamping members to said flanges.

4. A rail tie, comprising a base portion, a plurality of vertically disposed inclined 10 flanges arranged upon said base portion, rail receiving and supporting chairs positioned adjacent said flanges, rail clamping members receivable by certain of said flanges, said clamping members having formed upon 15 their outer ends, complementary rail receiving and supporting chairs, engageable with said first mentioned rail receiving and supporting chairs, an inclined shoulder formed upon one of the said flanges, means arranged 20 upon the opposite extremity of one of said clamping members engageable with said inclined shoulder whereby said clamping member may be forced laterally into engagement with its respective rail, and means 25 for securing said clamping members to said flanges.

5. A rail tie, comprising a base portion, a plurality of vertically disposed inclined flanges arranged upon said base portion, rail 30 receiving and supporting chairs positioned adjacent said flanges, rail clamping members receivable about certain of said flanges, said clamping members having formed upon their outer extremities, complementary rail 35 receiving and supporting chairs engageable with said first mentioned rail receiving and supporting chairs, an inclined shoulder formed upon one of said flanges and engageable with the opposite extremity of the adjacent clamp member for forcing the same 40

laterally into engagement with the respective rails for securing said clamping members to said flanges, and means engageable with said rail engaging chairs for preventing longitudinal movement of the rails. 45

6. A rail tie including a base portion, rail chairs including wedge portions and recessed feet, said feet being adapted to receive a rail base having a lug, and rail clamping members arranged to coöperate with the wedge 50 portions to clamp a rail in position.

7. A rail tie including a base portion, rail chairs upon the base including flanges and recessed seats a portion of the base terminating in wedge members, inclined shoulders on 55 the base; clamping members having wedge portions and coöoperating recessed feet and rail engaging flanges, said clamping members and supporting chairs being adapted to receive the rails having lugs, one of said 60 clamping members having portions adapted to engage the inclined shoulders, and a locking bolt having the portions arranged at right angles to each other for locking the clamp members in position on the base. 65

8. In a rail tie, the combination with the base having an opening and an inclined shoulder adjacent to the opening, a clamp member adapted to be fitted on to the base in engagement with the inclined shoulder 70 and over the opening, and a securing bolt having keys disposed at right angles to each other for engaging the openings and the clamp member.

In testimony whereof I affix my signature 75 in presence of two witnesses.

WALTER L. MITCHELL.
